Kent W. Benham, Gates Mills, Ohio, assignor to The Sanymetal Products Co., Inc., Cleveland, Ohio, a corporation of Ohio

Filed Dec. 15, 1958, Ser. No. 53,765

Term of patent 14 years

(Cl. D13—3)

Fig. 5

Fig. 1 is a perspective view of a pilaster and hinge bracket combination showing my new design, with portion at the top broken away for convenience of illustration;

Fig. 2 is a side elevational view thereof; and

Fig. 3 is a fragmentary bottom perspective view of the lower bracket portions.

Fig. 4 is a perspective view of another embodiment of my new design of pilaster and hinge bracket combination; and

Fig. 5 is a side elevational view of the embodiment shown in Fig. 4.

The essential features of my design reside in the portions shown in full lines.

I claim:

The ornamental design for a pilaster and hinge bracket combination, substantially as shown and described.
